G. J. RENLE

STRAIN EQUALIZER

Filed Oct. 22, 1927

Fig. 3.

Inventor

Gotthilf J. Renle

By Clarence A. O'Brien
Attorney

UNITED STATES PATENT OFFICE.

GOTTHILF J. RENLE, OF LEHI, NORTH DAKOTA.

STRAIN EQUALIZER.

Application filed October 22, 1927. Serial No. 223,055.

The present invention relates to a strain equalizing device, particularly adapted for use where it is necessary or desirable to produce an equal pull upon a pair of wires or 5 cables, as in fences, telephone or telegraphic wires.

The device is characterized by the fact that the pull on the pair of wires may be equalized. This result is produced by an exceedingly simple, strong and durable structure embodying a frame of arcuate formation with pulleys at the ends thereof and a chain or the like trained over said pulleys and means for engaging the frame with a 15 stretching mechanism.

A still further very important feature of the invention resides in the provision of a device of this nature which is thoroughly efficient and reliable in use, easy to manipulate, and otherwise well adapted to the purpose for which it is intended.

With the above and numerous other objects in view as will appear as the description proceeds, the invention resides in certain novel features of construction, combination and arrangement of parts as will be hereinafter more fully described and claimed.

In the drawing:
30 Figure 1 is an elevation of the equalizer embodying the features of my invention,
Figure 2 is another elevation thereof taken at right angles to that shown in Figure 1, and
35 Figure 3 is an enlarged detail sectional view taken substantially on the line 3—3 of Figure 1.

Referring to the drawing in detail it will be seen that the frame F is formed of a pair 40 of arcuate strips of flat like metal or other strong and suitable material, each strip being denoted specifically by numeral 5. The major portions of these strips 5 are disposed alongside of each other in abutment and held firmly together by a plurality of rivets 6. The extremities of these strips, however, are offset laterally to provide spaced parallel ears 7 between which are journaled pulleys 8. The strips 5 are formed with registering openings 9 and links 10 are engaged therewith and engaged with a ring 11. A chain or other suitable flexible element 12

extends between the ears 7 and is trained over the pulleys 8. At the extremities of the chain 12 there are mounted wire engaging elements 14.

The ring 11 is adapted to be engaged by a wire stretching mechanism or the like and the pull on the ring 11 caused by said mechanism will be imparted through the links 10 to the frame F and equalized through the chain 12 to the wire engaged in the elements 14 as will be quite apparent.

The present embodiment of the invention has been disclosed in detail merely by way 65 of example since in actual practice it attains the features of advantage enumerated as desirable in the statement of the invention and the above description. It will be apparent that changes in the details of construction, 70 and in the combination and arrangement of parts may be resorted to without departing from the spirit or scope of the invention as hereinafter claimed or sacrificing any of its advantages.

Having thus described my invention, what I claim as new is:

1. A strain equalizer of the class described comprising an arcuate frame, pulleys journaled in the ends of the frame, a chain 80 trained over said pulleys, wire engaging elements on the extremities of the chain.

2. A strain equalizer of the class described comprising an arcuate frame, pulleys journaled in the ends of the frame, a chain 85 trained over said pulleys, wire engaging elements on the extremities of the chain, a pair of links engaged with the frame equidistant from the center thereof, and a ring engaged with the extremities of the links.

3. A strain equalizer of the class described comprising a frame formed from a pair of arcuate strips disposed in abutment with each other throughout the major portion of their length, means securing said major portions together, the ends of the strips being offset laterally to form spaced parallel ears, pulleys journaled between the ears, a chain trained over said pulleys, wire engaging elements on the extremities of the chain.

4. A strain equalizer of the class described comprising a frame formed from a pair of arcuate strips disposed in abutment with each other throughout the major portion of

their length, means securing said major portions together, the ends of the strips being offset laterally to form spaced parallel ears, pulleys journaled between the ears, a chain
5 trained over said pulleys, wire engaging elements on the extremities of the chain, said major portions of the strips being formed

with registering openings equidistant from the centers of the strips, links engaged in said openings, and a ring engaged with said 10 links.

In testimony whereof I affix my signature.

GOTTHILF J. RENLE.
